UNITED STATES PATENT OFFICE.

GEORGE C. WEBER, OF CHICAGO, ILLINOIS.

OPENING DEVICE FOR RECEPTACLES.

No. 925,145.

Specification of Letters Patent.

Patented June 15, 1909.

Application filed April 13, 1908. Serial No. 426,783.

To all whom it may concern:

Be it known that I, GEORGE C. WEBER, a citizen of the United States, residing at Chicago, in the county of Cook and State of Illinois, have invented certain new and useful Improvements in Opening Devices for Receptacles, of which the following is a specification.

This invention is intended, more especially, for use in connection with cans, like blacking cans, which comprise a body portion and a cap or cover intended to be held thereon by friction, although the invention is adapted for use in connection with caps for bottles or other receptacles.

In cans of the style in question great difficulty is often experienced in removing the cap or cover, which frequently must be pried or otherwise forced from the can, thereby necessitating the use of some kind of a tool or implement and at the same time tending to injure or destroy the cover or the body of the can. In certain prior constructions an opening device, inserted between the cap and body of the can has been employed, but such mechanism is objectionable for the reason that the cover must either be especially formed to receive such an opening device or a space must be left, after the cover has been inserted, thereby providing imperfect and unsatisfactory sealing of the can.

The present invention is intended to obviate the objections above noted and at the same time provide an easy and efficient means for prying the cover from the can no matter how tightly it may be inserted thereon.

Another object of the invention is to obviate the necessity for the use of bolts, rivets, or other attaching means for securing the opening device in operative position, thereby providing an unpunctured can the cover of which may be applied without interference from the opening device.

The invention consists in the features of construction and combination of parts hereinafter described and claimed.

In the drawings Figure 1 is a side elevation of an ordinary blacking box having the opening device of the present invention applied thereto, the cover being closed onto the body of the can; Fig. 2 a similar view, showing the cover partially pried up from the body of the can and in condition for manual removal; Fig. 3 an enlarged sec-

tional detail of the lid of a can, showing the opening device applied thereto; Fig. 4 a perspective view of the opening device; Fig. 5 an edge view of a slightly modified form of the opening device; Fig. 6 a perspective view of a paint can, showing the method of applying the opening device thereto; and Fig. 7 a modified form of opening device intended for application to cans having extremely tight fitting caps or covers.

Referring to Figs. 1 and 2, the opening device is applied to a can having a body section 8 and a cover 9 slipped over the rim or edge of the body section and adapted to abut against the bead or flange 10 outwardly pressed from the body section. The rim of the cover is provided at a suitable point with an upturned lip 11 having a curved end cut on a circle having the adjacent end 13 of a slot 14 as a radius. The slot is cut in the bend or angle of the upturned lip 11, which lip is formed integrally with the edge of the rim with which it is connected.

The slotted lip serves as a socket for a key 15 which is entered through the slot and curved on its end 16, said curvature being such as will enable the key to swing within the slot without jamming or binding. Adjacent to the curved end 16, on the side of the key, is an outwardly projecting flange 17 which extends back from the curved end of the key for a distance substantially equal to the length of the slot, which brings the inner end of the flange into abutment with the end 13 of the slot 12 and brings the outer end of the flange into a position where it will engage the flange or bead 10 when the key is turned into the position shown in Fig. 2. The key is preferably curved to register with the curvature of the rim of the cover, and is of a length to extend beyond the curved end 12 of the lip 11 for a considerable distance.

The projecting portion of the key is provided, on its upper edge, with an outwardly projecting thumb piece or handle 18, which enables the user to swing the key into operative position; and in order to hold the key into proper operative position a tongue 19 is struck free from the lower edge of the key and outwardly bent at a point closely adjacent to the curved end of the lip 11, the distance between the end of the flange 17 and the tongue 19 being substantially the same as the radius of curvature of the curved end

12, so that when the key is turned it will swing in the arc of a circle and hold the flange 17 simultaneously into engagement at its opposite ends with the end 13 of the slot 5 12 and with the flange or bead 10, so that continued movement of the key will serve to pry up the lid from the body of the box.

The modified form shown in Fig. 5 differs from that previously described only in the 10 fact that the key, instead of being uniformly curved to register with the curvature of the rim of the lid is bent at an angle which serves to bring the key sufficiently close to the cover.

Fig. 6 shows the application of the opening device to a paint can in which the cap or 15 cover is of substantially lesser diameter than the body of the can, and is slipped onto a rim or lip 20 upwardly projecting from the flat top 21 of the can body 22. The construction of the cap or cover and the opening device attached thereto differs not at all from that previously described, the operation of 20 prying up the cap from the can being identical in both cases; Fig. 7 shows a duplicate 25 key the ends of which are identical in construction with the single key previously described and are connected by a curved body portion 23 provided with an outwardly projecting tongue or ledge 24, which serves as a 30 handle in operating the duplicate key. The construction of Fig. 7 is intended, more particularly, for use in connection with paint or other cans having covers fitting thereto with extreme tightness, which covers can best be 35 pried up by employing a key member which serves to simultaneously exert a prying action on both sides of the cap or cover.

The several styles of opening device herein shown all operate in precisely the same way 40 in that the cover is loosened by a prying action which is exerted in opposite directions against the body of the can and its cap. By forming the key in the manner indicated and securing it in place and holding it in 45 operative position in the manner shown, a very substantial leverage can be obtained the length of the key being determined with reference to the amount of pressure necessary to be exerted to pry up the cap or cover 50 of the body of the can or receptacle. Certain prior constructions employ a key having a handle connected therewith by a neck of reduced diameter and outwardly extending therefrom at right angles to the key. 55 This construction is objectionable in that the handle is liable to become broken or twisted when in use in removing tightly fitting covers. The present construction obviates this difficulty in that the strain on the 60 key is substantially all in a direct line with its vertical dimension so that it is not subjected to a twisting or torsional strain, which would tend to break it. At the same time the arrangement is one which brings the key 65 into close proximity to the rim of the cover

and obviates the necessity for providing a handle which outwardly projects from the cover to an objectionable degree.

What I claim as new and desire to secure by Letters Patent is:

70

1. A receptacle, comprising a body portion and a cover, one of the members having a rim adapted to slip over the end of the other member, a reversely turned lip secured to the rim and provided with a slot 75 at its bend or angle, an abutment on the other member, a key lying intermediate the lip and the adjacent wall of the member to which it is attached, and provided with an end adapted to be swung through the slot 80 to engage the abutment, and a handle portion connected to the end of the key opposite to that which engages the slot, substantially as described.

2. A receptacle, comprising a body portion 85 and a cover, one of the members having a rim adapted to slip over the end of the other member, a reversely turned lip secured to the rim and provided with a slot at its bend or angle, an abutment on the other member, 90 a key lying intermediate the lip and the adjacent wall of the member to which it is attached, and provided with an end adapted to be swung through the slot to engage the abutment, a handle portion connected to the 95 end of the key opposite to that which engages the slot, and a tongue adapted to ride over the end of the lip, substantially as described.

3. A receptacle, comprising two members, 100 one of the members having a rim or flange slipped over the end of the other member, the latter member being provided with a circumferential bead or ledge, a reversely turned lip on the first mentioned member 105 provided with a slot at its bend or angle and having one of its ends cut on a circle struck from the adjacent end of the slot as a center, a key member lying intermediate the lip and the wall of the member to which it is connected and having a curved end adapted to travel through the slot and having formed on its side adjacent to said curved end an outwardly projecting flange the ends of 110 which are adapted to simultaneously engage the bead or ledge and the end of the slot, and a handle portion connected to the end of the key opposite to that which engages the slot, substantially as described.

4. A receptacle, comprising two members, 115 one of the members having a rim or flange slipped over the end of the other member, the latter member being provided with a circumferential bead or ledge, a reversely turned lip on the first mentioned member 120 provided with a slot at its bend or angle and having one of its ends cut on a circle struck from the adjacent end of the slot as a center, a key member lying intermediate 125 the lip and the wall of the member to which 130

it is connected and having a curved end adapted to travel through the slot and having formed on the side adjacent to said curved end an outwardly projecting flange 5 the ends of which are adapted to simultaneously engage the bead or ledge and the end of the slot, a handle portion connected to the end of the key opposite to that which engages the slot, and a tongue outwardly pro-

jecting from the key and adapted to ride 10 over the curved end of the lip when the key is turned into opening position, substantially as described.
